METHODS OF PREPARING FLOTATION REAGENTS

Frederick R. Archibald, Toronto, Ontario, Canada, assignor to United States Steel Corporation, a corporation of New Jersey

No Drawing. Application July 5, 1951,
Serial No. 235,359

5 Claims. (Cl. 252—61)

1

This invention relates to improved methods of preparing flotation reagents which consist essentially of collectors of the fatty acid type and colloidal silica and are substantially free of alkali metal ions.

My co-pending application Serial No. 172,197, filed July 5, 1950, describes and claims the foregoing type of reagents and also flotation methods involving their use. Briefly these reagents consist of about 0.06 to 0.6 part by weight of colloidal silica to one part by weight of a collector of the fatty acid type on an anhydrous basis; they have a mol ratio of silica to alkali metals of at least 25 to 1; preferably they are premixed. These reagents are particularly useful for floating iron oxide minerals from siliceous gangue, where colloidal silica is a highly effective agent for wetting and depressing gangue particles and allowing the collector to float the iron oxide mineral particles.

My aforesaid application defines "collectors of the fatty acid type" as including higher fatty acids, such as oleic acid, palmitic acid, linoleic acid, lauric acid, myristic acid, stearic acid and tartric acid; esters of the higher fatty acids, such as their glycerol and glycol esters; resin acids, such as abietic acid, naphthenic acids; and various mixtures of the foregoing, but in each instance being substantially free of ions of alkali metals such as would be found in the sodium salts of the various acids. In the present application this same definition applies, but I also define "fatty acid material" as including all the foregoing substances, as well as their alkali metal soaps. As sources of fatty acid materials, I prefer crude mixtures of fatty acids and resin acids, such as tall oil, which is sold under the trade names "Opoil" and "Facoil," crude "soap skimmings" from the pulp and paper industry, or cottonseed "foots," all of which have the advantages of ready availability and low cost.

An object of the present invention is to provide preparation methods which produce improved pre-mixed reagents in which collectors of the fatty acid type and colloidal silica of low alkali metal content are more highly dispersed, and which reagents have enhanced wetting action on siliceous mineral particles.

A further object is to provide simplified and improved methods of preparing such reagents in which preferably the components are pre-mixed and treated with an ion exchange medium to remove alkali metal ions, although without sacrificing all the benefits of the invention, these components can be treated separately with the ion exchange medium and either subsequently mixed or added separately to an ore pulp.

2

According to the preferred way of practicing the present invention, a fatty acid material first is mixed with sodium silicate. Said fatty acid material can be any of those previously mentioned. An example is "Opoil" in which the fatty acids are chiefly oleic, linoleic and palmitic and the resin acid chiefly abietic. The fatty acid content is about 46 to 48.5% and the resin acid content about 42.2 to 45% (calculated as abietic). The sodium silicate can be any of the commercially available preparations. Such preparations commonly have a mol ratio of SiO_2 to Na_2O of about 3.2 to 1, a specific gravity of about 40° to 43° Baumé, and contain roughly 30% SiO_2 . An example is Philadelphia Quartz Company "N" brand. The proportions used are equivalent to about 0.06 to 0.6 part by weight of SiO_2 to 1 part by weight of collector of the fatty acid type as produced in the subsequent ion exchange reaction. Many of the fatty acid materials, such as the soaps, are readily dispersed in sodium silicate solution without additional dispersing agents, but where needed, as with the acids themselves, alkali or ammonium hydroxide can be added either in this first mixing step, or previously to the fatty acid, to act as a dispersing agent.

Next the mixture is diluted with water and roughly emulsified to form a solution having a maximum SiO_2 content of about 1.5%. In the example of "Opoil" and "N" brand sodium silicate, if the solution is diluted to 1% "Opoil," the maximum concentration of "N" brand sodium silicate (30% SiO_2) is about 5%, or if the solution is diluted to 1% "N" brand sodium silicate, the maximum concentration of "Opoil" is about 5%, to produce satisfactory reactions with the ion exchanger. The actual proportions used give the ratio of 0.06 to 0.6 part by weight of SiO_2 to 1 part by weight of collector of the fatty acid type in the finished reagent, these maximum concentrations being merely those that react satisfactorily with the ion exchanger.

Next the solution thus prepared is treated with an acid type ion exchange medium. This medium can be of any of the well known substances which are capable of exchanging hydrogen ions for sodium ions present in the sodium silicate, in the fatty acid material, and in the dispersing agent if used. Examples of such substances are natural and synthetic zeolite and certain synthetic resins which have hydrogen atoms in ion exchange positions, such as the phenolic resin sold by the trade name "Amberlite 1R-100H." Either the solution can be passed through a bed of ion exchanger or else granules of the exchanger can be agitated with the solution. During such

3

treatment the ion exchanger acquires alkali metal ions from the solution, but can be regenerated by treatment with an acid, as known in the art.

The effluent from the ion exchange is a highly dispersed solution of colloidal silica and collector of the fatty acid type and has a very low content of alkali metal ions, that is, a mol ratio of silica to alkali metals of at least 25 to 1. The pH of the original solution varies from 10 to 12 and that of the effluent from 2.5 to 3.5. The solution can be stabilized by addition of a small amount of sodium silicate as long as the alkali metal ion content is maintained within the limits hereinbefore stated. This solution can be used as a flotation reagent in the manner described and claimed in my aforesaid application; that is, it can be mixed with a finely divided pulp of iron oxide ore and siliceous gangue, which then can be treated in any standard or desired flotation cell. The colloidal silica effectively wets and depresses the gangue, while the collector of the fatty acid type floats the iron oxide minerals.

Pre-mixing the components before treating them with the ion exchanger produces a more highly dispersed and active reagent than when the components are mixed after such treatment or added separately to an ore pulp. While I do not wish to limit myself to any particular theory, I believe this improvement is due at least in part to the formation of the colloidal silica in the presence of fatty acid ions. According to this theory, the wetting action of colloidal silica on siliceous gangue is due partially to its affinity to calcium ions which usually are associated with this gangue. Fatty acid ions are known to have a strong affinity for calcium ions. Colloidal silica molecules which are formed in the presence of fatty acid molecules tend to conform in physical structure to the latter and consequently acquire some of the affinity of fatty acid ions for calcium ions, becoming in effect "tailor-made molecules."

Some of the benefits of the present invention can be achieved by treating a fatty acid material alone with an ionic exchanger and then either mixing it with previously prepared colloidal silica or adding the two separately to an ore pulp. In

4

introduce additional colloidal silica to the resulting product. This practice is particularly useful where the desired ratio of colloidal silica to collector is higher than desired for treatment with the ion exchanger.

Specific examples of ways in which reagents can be prepared according to the present invention and used in flotation processes are as follows:

EXAMPLE I

10 grams of crude tall oil ("Opoil") was mixed with 10 grams of sodium silicate solution (Philadelphia Quartz Company, "N" brand). The mixture was diluted with a little water, warmed on a hot plate, and shaken until roughly emulsified. The mixture was diluted to 1 liter with water and stirred with an electric stirrer until uniformly mixed. Next it was passed through an acid type ion exchange column and the resulting product was a milky colored emulsion.

15 A sample of classifier underflow from a closed circuit grinding and classification operation on taconite ore was selected for treatment. A reagent prepared as just described was added to the sample in an amount equivalent to 0.81 pound tall oil and 0.81 pound sodium silicate solution (approximately 0.25 pound colloidal silica on an anhydrous basis) per long ton of solids in the sample. In accordance with the third possibility described hereinbefore, additional colloidal silica was introduced in an amount equivalent to 0.81 pound sodium silicate solution (approximately 0.25 pound colloidal silica on an anhydrous basis) 20 per long ton of solids. After appropriate mixing the sample was treated by flotation and 39.6% of the sample weight was recovered as a flotation concentrate assaying 63.5% Fe and 6.0% acid insoluble residue. This concentrate was recovered 25 at a much coarser particle size and a higher grade than was being obtained in the regular operation after grinding much finer and using magnetic separators for treatment of classifier overflow. Screen analyses and grades of concentrates obtained by flotation of the classifier underflow and magnetic separation of the classifier 30 overflow were as follows:

Mesh Size	Flotation, Percent Weight		Concentrate Cumulative	Magnetic		
				Separator, Percent Weight	Concentrate Cumulative	
+200	47.8		71.9	6.1		15.2
200/270	24.1		100.0	9.1		100.0
-270	28.1			84.8		
	Fe	Insol	Fe/Insol	Fe	Insol	Fe/Insol
Grade of Concentrate	63.5	6.00	10.6	64.4	7.08	9.1

EXAMPLE II

this instance the fatty acid material can be any of those previously mentioned, and it is treated in concentrations up to 20% with any of the same 65 ionic exchangers. This alternative way of practicing the invention retains the benefits of substantially eliminating alkali metal ions and of producing a highly dispersed collector of the fatty acid type, but of course it loses the advantages gained by forming the colloidal silica in the presence of fatty acid.

A third possibility is to pre-mix the fatty acid material and sodium silicate and treat them together with the ion exchanger, as in the preferred practice already described, and then to in-

umn in a glass tube. The effluent was used as a flotation reagent in the manner next described.

A sample of iron ore classifier underflow containing approximately 1300 grams of solids and representing the circulating load in a grinding and classification circuit was placed in a laboratory flotation cell and conditioned with 100 ml. of the effluent thus prepared for 6 minutes. The pulp was diluted to the normal operating level and froth removed. The rougher concentrate was returned to the cell and twice re-cleaned, producing a cleaner concentrate assaying 65.25% Fe and 5.64% acid insoluble residue, equal in weight to 30.8% of the original sample. The reagents used were equivalent to 1.74 pounds each of soap skimmings and sodium silicate solution (0.52 pound of colloidal silica on an anhydrous basis) per long ton of solids.

For comparison, to show the advantage of pre-mixing the fatty acid material and sodium silicate and treating them together with the ion exchanger, a similar ore sample was treated by flotation with these agents prepared by separate treatment with an ion exchanger. Other conditions were identical. This treatment yielded 28% of the weight of the sample as a concentrate assaying 64.05% Fe and 6.2% acid insoluble residue.

From another sample of classifier underflow taken under different operating conditions and using the pre-mixed reagent of the present example, 42.8% of the sample weight was recovered as a concentrate assaying 65.85% Fe and 5.66% acid insoluble.

EXAMPLE III

For comparative tests two reagents were prepared similarly except that the first lacked treatment with an ion exchanger. This first reagent was prepared by mixing 1 gram of ammonium hydroxide with 10 grams crude tall oil, warming and then diluting to one liter. 10 grams "N" brand sodium silicate was diluted with water to a volume of 1 liter. Equal volumes of ammonia-tall oil and diluted sodium silicate were mixed and produced a cloudy and somewhat viscous solution. The second reagent was prepared by passing some of this same solution through an acid type ion exchange medium.

For comparison of the effectiveness of the two reagents, a sample classifier underflow as described in Example I was divided into two portions containing approximately 800 grams of solids each. In each flotation test the pulp was added to a laboratory flotation cell and conditioned with 150 ml. of reagent solution. Flotation and one re-cleaning were carried out on each utilizing the two reagents prepared as described, following usual procedures and without further reagent additions. The results were as follows:

	Percent Weight as Concentrate	Analysis Concentrate		
		Fe	Insol	Fe/Insol
First Reagent	46.5	61.35	7.94	7.73
Second Reagent	46.6	64.05	6.30	10.17

In the first test the froth was voluminous, soapy and persistent after collection. The concentrate was not of acceptable grade. In the second test the froth was heavily mineralized, dry, fast forming and collapsed readily after collection. The grade of concentrate was acceptable.

70 75

EXAMPLE IV

10 grams of soap skimmings were diluted with water to a volume of 1 liter and stirred until substantially all dissolved or dispersed. The mixture was run through an acid type ion exchanger set up in a vertical glass tube 2 inches in diameter. The column of ion exchange resin ("Amberlite 1R-100H") was 15 inches high. The effluent from the exchanger was used as a flotation collector in conjunction with colloidal silica having a mol ratio of silica to alkali metal ions of at least 25 to 1.

A sample of classifier underflow pulp was taken from a closed circuit as in the preceding examples and split to give representative portions of about 1300 grams of solids each. One such portion was placed in a laboratory flotation cell and conditioned with 50 ml. colloidal silica solution for three minutes. The colloidal silica solution contained silica equivalent to approximately 3 grams SiO₂ per liter. 75 ml. of the fatty acid collector next was added and conditioning carried on for five minutes more. The pulp level was raised to normal operating level by addition of water. Froth was removed for 5 minutes. The rougher concentrate thus obtained was returned to the cell using the original flotation liquor for dilution, and again froth was removed in the usual way. One more re-cleaning was performed in the same manner. The total reagents used were equivalent to 1.30 pounds soap skimmings and 0.36 pound sodium silicate (0.26 pound silica on an anhydrous basis) per long ton of ore. The sodium silicate had been converted to colloidal silica solution by passing diluted water glass through an acid type ion exchanger. The flotation resulted in a recovery of 33.4% of the weight of the sample in a concentrate assaying 64.65% Fe and 6.54 acid insoluble residue.

EXAMPLE V

A similar sample of classifier underflow was treated by flotation with the same reagents in larger quantities, namely, the equivalent of 2 pounds of soap skimmings and 1 pound sodium silicate (0.30 pound silica on an anhydrous basis) per long ton of ore. By one re-cleaning of the rougher concentrate, 59.1% of the total sample weight was recovered in a product assaying 63.8% Fe and 7.24% acid insoluble.

From the foregoing description it is seen that the present invention affords a simple method of preparing a highly effective reagent for floating iron ore minerals from siliceous gangue. As best shown by the comparative tests of Example II, reagents in which the fatty acid type material and sodium silicate are mixed together before treatment with the ionic exchanger produce better results than reagents in which the two are separately prepared, although the latter still are effective reagents.

While I have described only certain preferred ways of practicing the invention, it is apparent that modifications may arise. Therefore, I do not wish to be limited by the specific disclosure, but only by the scope of the appended claim.

I claim:

1. A method of preparing pre-mixed flotation reagents, which consist essentially of collectors of the fatty acid type and colloidal silica in proportions of about 0.06 to 0.6 parts by weight of colloidal silica to one part by weight of collector on an anhydrous basis and have a mol ratio of silica to alkali metals of at least 25 to 1, comprising treating sodium silicate and an alkali

metal soap of an acid of the group consisting of higher fatty acids, resin acids, naphthenic acids and mixtures thereof, both in dilute water solution, with an acid type ion exchange medium which removes alkali metal ions therefrom.

2. A method as defined in claim 1 in which the dilute water solutions of soap and sodium silicate are mixed together before treatment with the ion exchange medium.

3. A method as defined in claim 1 in which the dilute water solutions of soap and sodium silicate are treated separately with the ion exchange medium and subsequently mixed.

4. A method of preparing pre-mixed flotation reagents, which consist essentially of collectors of the fatty acid type and colloidal silica in proportions of about 0.06 to 0.6 parts by weight of colloidal silica to one part by weight of collector on an anhydrous basis and have a mol ratio of silica to alkali metals of at least 25 to 1, comprising mixing water solutions of sodium silicate and an alkali metal soap of an acid of the group consisting of higher fatty acids, resin acids, naphthenic acids and mixtures thereof, diluting the mixture with water to a maximum

silica content of about 1.5%, and treating this diluted mixture with an acid type ion exchange medium which removes alkali metal ions therefrom.

5. A method of preparing a fatty acid collector for use in flotation comprising treating with an acid type ion exchange medium a water solution of an alkali metal soap of an acid of the group consisting of higher fatty acids, resin acids, naphthenic acids and mixtures thereof, and thus removing alkali metal ions therefrom.

FREDERICK R. ARCHIBALD.
